(57) **CLAIM**

The ornamental design for a shoe sole, as shown and described.

DESCRIPTION

FIG. 1 is a perspective view of a shoe sole, showing the design; and,

FIG. 2 is a bottom view of the shoe sole shown in FIG. 1. Broken lines in the figures are for purposes of illustrating portions of the shoe sole that form no part of the claimed design.

1 Claim, 2 Drawing Sheets

FIG. 1

FIG. 2
